SLICING MACHINE

Joseph Folk, La Porte, Ind., assignor to U. S.
Slicing Machine Company, La Porte, Ind., a
corporation of Indiana

Application June 30, 1930, Serial No. 464,823

22 Claims. (Cl. 146—102)

The present invention relates to a slicing machine and particularly that type of a slicing machine in which the knife is operated independently of the work holder so as to permit the work holder and knife to be operated at any desired speeds, and particularly any desired speed relatively to each other. Preferably the knife is motor driven and the work holder is manually actuated.

One object of this invention is to so arrange the various parts of the slicing machine that there is a clear space adjacent the knife on the side away from the work holder to permit the operator of the slicing machine to more effectively remove the slices as they are cut. A clearance space below the knife permits one to readily remove scraps of material which fall below the knife and enable one to wipe up the grease that drops from the knife onto the surfaces therebelow.

Prior known machines were so constructed as to render the space beneath the knife practically inaccessible. In some machines it has been the practice to use small scrap pans which may be slipped into a narrow place beneath the knife to receive the grease and the scraps which fall from the knife. However, this arrangement has not proved entirely satisfactory and only adds to the cost of the machine. Furthermore, it does not remove all of the scraps or grease formed by the knife and the remaining particles must be cleaned out by some means and it is not very easy to do this due to the arrangement of the various parts of the machine.

More specifically an object of this invention is to so arrange the knife supporting bracket that the same extends to the rear of the machine in a direction backwardly and downwardly and connects with the base of the machine at a position substantially at the rear edge of the cutting knife. This arrangement leaves the space beneath the bearing for the knife entirely free of any obstruction and one may position a flat slice supporting platform adjacent the knife and in such a position that the slice supporting platform may extend beneath the knife as well as adjacent the cutting plane of the knife on the side opposite to the work holder.

Another object of this invention is to mount the slice receiving platform so that the same may be readily removed for cleaning purposes.

Another object of this invention resides in the improved form of slice deflector which is used to deflect the slices away from the knife.

Another object of this invention is an im-

proved motor mounting, the motor being so mounted as not to obstruct the space beneath the knife and yet so arranged as not to materially increase the overall dimensions of the slicing machine.

Another object of this invention resides in the provision of a novel form of knife guard which ordinarily is so positioned that the top edge of the knife as well as the rear edge of the knife is substantially protected, but which can be quickly moved to a position in which the upper edge of the knife may be exposed for sharpening purposes.

A very important object of this invention is to provide an improved form of gage plate for gaging the thickness of the slices being cut and which may be quickly moved to such a position that the same may be readily cleaned without detaching the same from the slicing machine.

In constructing the work holder I prefer to use an operating handle for causing the work holder to move towards the cutting plane of the knife and simultaneously act as a means which may be used by the operator to manually reciprocate the work support relatively to the knife.

A still further object of this invention resides in providing an improved form of support for the slice being cut. This support is adapted to lie in front of the cutting edge of the knife and adjacent thereto at all times during the cutting operation to support the lower edge of the slice as the same is being cut. This support furthermore is so arranged that it will move vertically and always lie in the same plane as the supporting surface of the work support or in the same position relatively to said plane. This is particularly desirable in the machine which I have disclosed since in this machine the supporting surface is at an angle to the horizontal.

Another object of this invention resides in the provision of a suitable guard plate which prevents the substance from rubbing against the surface of the knife after the substance has passed the cutting edge thereof. This guard plate is readily detachable for the purpose of cleaning. I preferably employ a dished knife and arrange the guard plate within the hollow portion of the dished knife. This guard plate is preferably provided with grooves for the purposes hereinafter specified.

A still further object of my invention is to provide a machine in which a slice receiver may be moved bodily with the work table.

When using a slice receiver of this nature, I prefer to utilize the space below the cutting knife for the purpose of permitting the slice receiver to move beneath said knife, so that small scrape of meat as well as slices may be deposited on the slice receiver. Also with this arrangement the slice receiver may pass beneath the knife and yet intersect the cutting plane thereof.

In the drawings—

10 Fig. 1 is a side elevational view of a machine embodying my invention;

Fig. 2 is a side elevational view looking at the slicing machine from the side opposite to that in Fig. 1;

15 Fig. 3 is a section on the line 3—3 of Fig. 2;

Fig. 4 is a section taken substantially along the line 4—4 of Fig. 2, the slicing machine carriage having been moved to a position at the other end of its travel;

20 Fig. 5 is a section taken on the line 5—5 of Fig. 1;

Fig. 6 is a fragmentary side elevational view of the improved form of slice supporting member and showing its relation with respect to the 25 work support and the slicing knife;

Fig. 7 is a section taken substantially along the line 7—7 of Fig. 6;

Fig. 8 shows the construction of the slice supporting member;

30 Fig. 9 shows the manner of attaching a slice support to the work holder to cause the same to move with said work holder;

Fig. 10 is a view looking in the direction of 10—10 in Fig. 9;

35 Fig. 11 is a sectional view showing the manner in which the knife is driven and further illustrating the slice deflector mounting;

Fig. 12 is a plan view of the slice receiver shown in Figs. 9 and 10;

40 Referring more particularly to Figs. 1, 2, 4 and 5, it will be noted that the slicing machine comprises a base member 1 supported by means of rubber feet 2, these rubber feet comprising suitably shaped members having projecting portions

45 extending into suitable openings in the underside of the base. On this base member 1, I mount a combined cover guard and guide rod support 3. This support comprises the upstanding bracket members 4 secured to the base member

50 by means of the screws 5 and a connecting cover portion 6 having a cross-section as best illustrated in Fig. 4. At one side the member

3 is provided with a guard portion 7 which is a continuation of the cover portion 6. A guide

55 rod 8 best illustrated in Fig. 5 is mounted in the end brackets 4 and is held against longitudinal movement in the end brackets by means of the screws 9 and washers 10. Any other suitable means however, may be used to hold this

60 guide rod in place. Surrounding this guide rod adjacent the brackets 4 are felt washers 11 which act to cushion the movement of the carriage (presently to be described) as the same reciprocates along the guide rod and approaches

65 the end of its travel in either direction. Arranged in spaced parallel relation with the guide rod 8 is a guide bar 12. This guide bar is secured to the base by means of the screws

70 13 and is preferably square in cross-section as best illustrated in Fig. 4. A casting indicated

generally as 14, has a bearing portion 15 surrounding the guide rod 8 and a downwardly

75 projecting portion 16 which has a plate 17 fastened thereto at 18 and this plate is adapted to

abut against the lower side of the guide bar

12. The upper part of the guide bar abutting against a horizontally extending portion 19 in the downwardly extending portion 16 is adapted to receive a lubricant retaining member, preferably of felt, and a quantity of lubricant is introduced into the opening 20 through the opening 22. The guide bar 12 therefore prevents rotative movement of the casting 14 about the guide rod 8 and further assists in supporting the casting 14.

10 The casting 14 is adapted to support the V-shaped work holder 23. This work holder comprises a V-shaped casting 24 provided with the downwardly extending bosses 25 which are secured to the casting 14 by means of the bolts 26. The upper surface of the casting 24 is covered with a piece of sheet metal 27 upon which the substance is adapted to be supported. This is fastened onto the casting 24 by means of the bolts 28.

20 Referring now more particularly to Figs. 2, 4 and 5, it will be seen that the knife supporting

bracket comprises a base plate 29 and webs 30 and 31. These webs are relatively thin, and it will be noted from an inspection of Figs. 2

and 4 that the web 30 extends backwardly and downwardly from the bearing support 32 which

is adapted to rotatably support the knife, thus

leaving a relatively clear space directly beneath

the knife and practically all the way to the

rear of said knife. The web 31 extends up-

wardly from the base plate 29 and then inclines

toward the bearing support 32, thus providing

a great amount of clearance for the operator's

hand and the slice both below the knife and

adjacent the cutting plane thereof. Furthermore, this arrangement permits me to use a

slice receiver which will move with the sub-

stance support and in a manner which will later

be described.

40 The base plate of the knife supporting bracket is adjustably mounted on the base 1 by means

45 of bolts 29' passing through slots 28' in the base. The slots extend in a direction toward

the cutting plane of the knife so that as the

edge of the dished knife is ground and worn

away, the cutting edge of the knife may be positioned close to the edge of the work holder.

Due to the grinding unit 52, motor 42, guard 38

and shield 121 being also supported on the

45 bracket the same are moved bodily with the

knife so that their adjustment with respect

thereto is not changed when the bracket is ad-

justed.

50 In Fig. 4 it will be noted that the bearing sup-

port 32 receives the bushing 33 and the bushing

33 in turn supports the antifriction bearings 34

which support the knife shaft 35. A driven

55 wheel 36 having a V-shaped groove 37 in the

periphery thereof is keyed to the shaft 35 and

is adapted to rotate the shaft 35 when driven

as hereinafter specified. A dished knife 38 has

60 a pin 39 extending therethrough and through

the hub of the driven wheel 36 so as to prevent

relative rotation between the driven wheel 36

65 and the knife 38. A bolt 40 and washer 41 are

used to secure the knife on the shaft 35 and

hold the same against longitudinal movement

along the shaft.

70 The set screw 34' and lock nut 35' are used

to lock the bushing 33 in adjusted position lon-

75 gitudinally of the shaft 35 as well as to prevent

rotation thereof.

With this adjustment the knife can be posi-

tioned as close as desired to the edge of the

75

work holder 23. It is important that the cutting edge of the knife be as close as possible to the edge of the work holder so that when a slice is cut the bottom edge thereof will not be ragged and in order that too many scraps may not be produced.

A motor 42 is secured to the web 31 in the following manner:

The web 31 is provided with the bosses 43 which engage the cylindrical outer surface of the motor 42 and have surfaces substantially conforming to such cylindrical surface. A strap 44 secured by means of the screws 45 to the web 31 extends around the motor and has a member 46 secured to the other end thereof. A bolt 47 extends through the web 31 and is received within a suitably threaded opening in the member 46. The bolt 47 is rotatable in the web 31. It will be seen by this arrangement that when the bolt 47 is rotated in the proper direction, the member 46 will be drawn toward the web 31 to thereby increase the tension in the strap 44 and draw the motor 42 against the bosses 43.

The motor has a rotor shaft 48 which carries a driving pulley 49 at the end thereof adjacent the knife. This pulley 49 has a V-shaped groove therein similar to the groove 37 in the driven wheel 36. A V-shaped driving belt 50 is trained over the pulleys 36 and 49 so that when the motor is rotating, the knife is driven through the intermediary of the pulleys 49 and 36 and the belt 50. A switch 51 mounted on the web 31 is suitably connected to the motor for turning the motor on and off as desired. The wires leading to the motor have not been shown, but it is obvious that this motor may be connected to a suitable source of electricity in any desired manner.

By providing the strap 44 and bolt 47 for tightening the same the motor may be moved towards and from the knife as desired. This is necessary for the purpose of aligning the driving pulleys 49 and 36 when the knife is adjusted towards or away from the work holder so that the belt will not become worn due to unaligned pulleys or tend to impart irregular movement to the knife.

A grinding unit 52 of well known construction and comprising the grinders 53 and 54 is rotatably and longitudinally movable in the supporting bracket 55 by means of a supporting member 56. This bracket 55 is adjustably mounted for movement towards and from the knife by means of screws 55' which pass through slots 56' and are threaded into the boss 57'. In the position shown the grinders are out of operative position and while the grinders are in this position I prefer to have the upper edge of the knife covered by a suitable guard 57. This guard 57 is substantially U-shaped in cross-section as best illustrated in Fig. 4 and is pivoted at its lower end to the web 30 and in the following manner: A bracket 58 secured by the screws 59 to the web 30 has an offset portion 60. A thumb screw 62 is threaded into the guard and passes through the offset portion 60 to thereby form a pivot about which the guard may be moved.

A casing 63 extends around the pulleys 36 and 49 and protects the same. At the same time this casing prevents the operator from being injured if and when the belt 50 breaks. On top of this casing I mount a bracket 64 secured to the casing by means of a screw 65. This

bracket 64 has an arcuate slot 66 therein. When the bracket 64 is in place, the center about which the arcuate slot 66 is generated lies substantially at the center of the thumb screw 62. A bolt 67 passes through the side of the guard 57 at the upper end thereof and also passes through the arcuate slot 66. A nut 68 screw threaded on the end of the bolt 67 is used for the purpose of clamping the guard in adjusted position. An operating handle 69 is rigidly secured to the guard at a point on the outer surface thereof.

When it is desired to sharpen the knife, it is only necessary to loosen the nut 68 and move the guard in a clockwise direction as in Fig. 1 to position the same in the dotted line position shown in that figure, thereby leaving the space directly above the center of the knife free of any obstruction. At the same time the guard 57 acts to guard the edge of the knife and prevent anyone from accidentally cutting himself on the knife at the rear edge thereof. The grinding unit 52 may then be moved vertically and then rotated horizontally to position the grinders 53 and 54 over the knife in a well known manner, the slot 70 being provided for this purpose. A pin (not shown) moves in the slot 70 in a well known manner to guide the movements of the grinding unit 52 and for preventing fouling of the knife or the improper use of the grinders. Ordinarily it is not necessary to loosen the thumb screw 62 when it is desired to move the guard so that the knife may be ground, but in case the thumb screw 62 has been tightened a considerable amount, one may have to loosen the thumb screw 62 as well as the nut 68.

One way to gage the thickness of the slice being cut is to provide a gage plate. Such a gage plate is generally mounted in a plane parallel to the cutting plane of the knife and is adapted to move through successive parallel positions so that the thickness of the slice may be varied. In the embodiment of my invention shown in the accompanying drawings, I have illustrated an improved form of gage plate which has the advantage over prior devices of being more readily cleaned and which permits the operator to have more room for using his hand to withdraw slices as they are cut and is more simple in its construction than any of the prior art devices. In addition the gage plate is adapted to carry a guard which guards the forward edge of the knife. Therefore, when the gage plate is moved to the position wherein it is adapted to be cleaned, the forward edge of the knife is exposed for the purposes of cleaning or inspection. This gage plate is best shown in Figs. 1, 2 and 5. A bracket 71 is rigidly mounted at one end of the base 1 and is held in place by means of the bolts 72. This bracket has bearings in the opposite ends thereof adapted to rotatably support the shaft 73, and also permit longitudinal movement of the shaft in these bearings. The end of the shaft which is adjacent the cutting plane of the knife carries a gage plate designated generally as 74. This gage plate has a bearing portion 75 secured to the shaft 73 by the pin 76 or any other suitable fastening means. The gage plate comprises a flat vertically disposed portion 77 and a reinforcing rib 78. The edge of the gage plate adjacent the knife is curved to substantially the same curvature as the edge of the knife, or rather the center of curvature of the forward edge of the gage plate 75.

has its center of curvature at substantially the same point as the center of rotation of the knife. The vertical surface of the gage plate which lies adjacent the work holder 23 is grooved as at 80 5 to form spaced ribs between the grooves. This reduces the resistance which the gage plate offers to the movement of the substance thereover. The forward edge of the gage plate carries a guard 81 secured thereto by suitable screws 82 10 or the like. This guard, together with the guard 57, substantially guard the entire edge of the knife with the exception of that part which is at the bottom. The guard 57 and the guard 81 may be made of such a length as to meet, or at 15 least substantially meet at their opposed ends.

The spaced ribs and grooves also keep the gage plate cleaner and the same also permit the gage plate to be more readily cleaned by a few strokes of a cleaning cloth. With flat plates a 20 considerable suction is produced between the plate and substance and this tends to draw a considerable amount of grease from the substance being sliced and consequently the plate becomes coated very quickly. It will also be noted that the gage plate is relatively low to reduce the resistance offered to the movement of the substance thereover, due to the fact that with large substances only a fractional part of the substance is in contact with the gage plate.

30 As stated before, the shaft 73 is capable of being moved longitudinally within the bearings of the bracket 71. In order to keep the guard plate from rotating however, during the normal use thereof, I provide a boss 83 on the member 35 3 at a point near the junction between the portion 7 and the portion 6 thereof. I also provide the plate 71 with a pin 84 having an enlarged head 85 and a slot 86, the latter extending substantially the entire exposed length of 40 the pin. The head 85 normally has a larger overall dimension than the diameter of the opening 87 in the boss 83 so that when the head 85 is forced into the opening 87, the parts thereof on opposite sides of the slot 86 are moved 45 towards each other, and this causes the two portions of the enlarged head to exert an outward frictional force on the side walls of the opening 87. This prevents the gage plate from rattling and also guides the gage plate along a 50 predetermined path without a substantial amount of friction. The pin 84 extends through the gage plate and is locked in place thereon by means of the nut 88.

By the arrangement just described, it will be 55 seen that the shaft 73 may be moved longitudinally of its axis so as to position the face of the gage plate in successive parallel planes at varying distances from the cutting plane of the knife. The normal movements however, 60 of the shaft longitudinally of its axis are limited so that the pin 84 cannot move out of the opening 87 and thus destroy the value of the pin 84 as a guiding element. This is accomplished in the following manner:

65 The shaft 73 is formed with screw threads 89 at one end thereof, and is internally threaded at the same end to receive the screw 90 having the operating head 91. A washer 92 is interposed between the end of the shaft and the head 91. This washer is adapted to slide longitudinally in the recess 93 provided in the gage plate 70 96. This knob 94 has a screw 95 rotatably mounted in the enlarged portion 96, and the inner end of this screw engages the threads 89 on the shaft 73. The top of the 75

screw 95 is below the outer peripheral surface of the enlarged portion 96, and on the outer peripheral portion I secure a cylindrically shaped plate 97 carrying designations indicating the sizes of the slices to be cut. A pointer 98 secured to the bracket 71 is adapted to co-operate with the designations on the plate 97 to indicate the position of the gage plate.

A spring 99 abutting against the collar 100 secured to the shaft 73 and abutting against 10 one of the bearings for the shaft normally urges the shaft upwardly as viewed in Fig. 5, or in a direction to carry the gage plate away from the cutting plane of the knife. The permitted movement of the shaft 73 in an upward direction in Fig. 5 is limited by the engagement of the enlarged portion 96 on the knob 94 engaging the adjacent bearing for shaft 73. The position of the knob 94 on the shaft 73 in turn is determined by the position of the screw 95 15 with respect to the thread 89 on the shaft 73. It will be noted that when the knob 94 is rotated in a counter-clockwise direction as viewed in Fig. 1, the end of the screw 95 will travel in the thread 89 towards the adjacent end of the 20 shaft 73 thereby drawing the washer 92 into the recess 93. Naturally the amount of travel for the screw 95 is limited by the engagement of the washer 92 with the bottom of the recess 93. The parts are preferably so proportioned 25 that one complete movement of the knob 94 moves the washer 92 from one end of the recess 93 to the other end thereof. As the knob 94 is rotated in a counter-clockwise direction, the spring acts to move the shaft 73 in an upward direction as viewed in Fig. 5, and thereby carries the gage plate 74 away from the cutting plane of the knife.

The operation of this gage plate is as follows: The substance to be sliced is placed on the 40 substance support or work holder 23, and if desired may be moved by hand or any other suitable means against the grooved surface 80 of the gage plate. If the gage plate has been moved away from the cutting plane of the knife, 45 then the forward edge of the substance being sliced will be past the cutting plane of the knife a distance equal to the thickness of the slice desired to be cut. When the work holder is thereafter moved along the guide rod 8, the portion of the substance projecting over the cutting plane is severed by the knife. The position of the gage plate 74 will, of course, determine the thickness of the slice and the indications on the cylindrical plate 97 may be used to predetermine the thickness of the slice to be cut.

It sometimes becomes desirable to clean the gage plate and also to clean the space beneath the gage plate and between the gage plate and the member 3. In order to do this, it is only 55 necessary to move the screw 98 by means of the head 91 to the dotted line position shown in Fig. 5. Thereafter the knob 94 may be given several complete movements in a counter-clockwise direction and this will cause the shaft 73 to move 60 a greater distance than is normally permitted, as the washer 92 will merely slide along the screw 90 when it strikes the bottom of the recess 93 and will not limit the movement of the shaft 73 until the head 91 of the screw 90 is engaged by the washer. This amount of permitted movement of the shaft 73 is sufficient to move the pin 84 out of the opening 87. Since the shaft 73 is now free to rotate in the bearings of the bracket 71, the gage plate may be moved to 65 70 75 78

the dotted line position shown in Fig. 5 without having actually dismantled the gage plate or the supporting mechanism therefor. It will readily be seen that the gage plate may be cleaned very 5 thoroughly and that the parts of the machine adjacent the gage plate may be cleaned before again positioning the gage plate in its original position. Of course when the pin 84 is again positioned within the opening 87, the screw 90 10 is moved to the full line position shown in Fig. 5, so that normally there is no chance for the pin 84 to come out of the opening 87.

No claim is made herein broadly to a gage 15 plate which is both slidable to effect its gage functions and movable to inoperative position for cleaning and the like, as such construction is shown and broadly claimed in my co-pending application, Serial No. 637,246, filed October 11, 1932. The claims in the instant case are all 20 limited to features of construction in connection with the gage plate which are not shown in the construction of said companion case.

The operator may be leaning a little to the 25 left of the cutting plane of the knife while the slices are being cut, to better enable him to handle the slices which he does with his left hand. At the same time he must move the substance support past the knife and the substance clamp towards the gage plate and therefore it is quite 30 desirable that the gage plate be as low as possible so that he may observe the movements of his right hand. Furthermore, if he is not leaning to the left of the gage plate he will be able to more readily see the slices as they are cut due 35 to the lowness of the gage plate. The gage plate is also relatively thin and offers substantially no obstruction to the operator's view as he stands in line with the cutting plane.

The feeding mechanism for the gage plate is 40 located substantially entirely on the work holder side of the cutting plane and this leaves the space at the left of the cutting plane clear as well as positioning the feeding mechanism in the most convenient place for the operator. In some 45 devices it has been proposed to place operating means for the gage plate beneath the slice receiving platform. Such an arrangement necessitates the raising of the entire machine in order that this mechanism be accessible for 50 cleaning or repair. With my arrangement the slice receiving platform can be made very low and be entirely free of any obstruction. The feeding mechanism is also in a convenient place for repair and cleaning.

55 It is well known that when a substance being sliced passes the cutting edge of the knife, that portion of the substance which remains on the work holder or support will cause a retarding effect on the knife if permitted to engage the 60 surface thereof. I overcome this difficulty first, by providing a dished knife, and secondly, by providing a low guard plate 101. This guard plate has the grooves 102 on the surface thereof adjacent the substance being sliced for the same 65 purpose as the grooves 80 in the gage plate. The outer edge 103 of the guard plate has a curvature whose center is substantially in the center of rotation of the knife so that the edge 103 always is substantially at the same distance 70 away from the cutting edge of the knife at all points thereof. The guard plate 101 has pins 104 secured thereto at the bottom portion thereof. These pins have a screw threaded portion 105 passing through the lugs 106 and are held 75 in place by means of the lock nuts 107. Bosses

108 on the member 3 have suitable openings therein for receiving the pins 104. The pins 104 have a relatively close fit with the openings in the bosses 108 so as to hold the guard plate 101 in a predetermined position, and to also prevent any relatively great amount of vibration thereof. These pins 104 are preferably split as at 109 as best illustrated in Fig. 4. This is so that the pin will exert a frictional resistance against accidental movement thereof in the 10 openings in bosses 108. However, the frictional resistance should not be so great that the guard plate cannot readily be removed.

As best illustrated in Figs. 2 and 4, the base 1 is provided with upstanding bosses 110 upon 15 which the slice receiving plate 111 is adapted to rest. At spaced points on the base and adjacent the edges of the slice receiving plate 111, I provide a plurality of thumb screws 112. Each of these thumb screws passes through a retaining 20 plate 113 having angularly offset portions 114 and 115 at the top and bottom respectively. The receiving plate has one side thereof abutting against the guard portion 7 of the member 3 at 116 (see Fig. 4) and another edge of said 25 slice receiving plate abuts at 117 (see Fig. 2) against the base plate 29. As best illustrated in Fig. 2 at the right, each of the thumb screws has a spring 118 surrounding the same and interposed between the bottom of a recess 119 30 and the plate 113, the thumb screw being screw threaded in the base 1. The upper angularly offset portions 114 of the plates 113 engage the beveled edges of the slice receiving plate 111 and the lower angularly offset portions of the plates 35 120 within the recesses 121. It will therefore be seen that as the thumb screws 112 are rotated to clamp the plates in a direction towards the slice receiving plate, the angularly disposed 40 upper and lower portions 114 and 115 will tend to draw the plate 111 firmly against the bosses 110. Furthermore, when the thumb screws are released it is not necessary to entirely remove the thumb screws in order to release the plate 45 111 for when the thumb screws have been loosened a predetermined amount, the plates 113 may be rotated at right angles to the positions shown in the figures so as to be below the lower surface of the plate 111. The plate there- 50 after may be removed for the purposes of cleaning or for any like purpose.

I provide a deflector plate 121 which is substantially a section of a cone and I mount this 55 in such a manner as to position the forward edge 122 thereof substantially symmetrically with the cutting edge of the knife 33 and removed slightly from the cutting edge of said knife. The purpose of this deflector is to deflect the slices away from the knife after they 60 have been cut and throw the same onto the slice receiving plate 111 or else position them so that the operator may grasp the slice as it is being formed and carry the same directly towards the rear of the machine while the rest of the slice 65 is being cut. By providing a large open space below the bearing support 32 and for a considerable distance to the rear thereof, the operator is enabled to move his hand and the slice carried thereby in the same direction so 70 that the slice will remain straightened out and in such a condition that the operator may place it on the slice receiving plate 111 so as to be ready for the next slice to be cut. At the bottom of the deflector 121 I provide an extension 123 75

and this extension is adapted to extend beyond the cutting edge of the knife to assist the guards 81 and 57 in protecting the operator from the knife. I so mount the deflector 121 however, 5 that the same may be quickly moved to a position where it may be cleaned and to a position such that the knife may be cleaned beneath the deflector. Or alternately I provide a means for quickly removing the deflector entirely. This 10 means is best illustrated in Figs. 2 and 3 and comprises an arc shaped member 124 having a conical bearing point 125 fitting in the co-operating recess in the boss 126. Diametrically opposed to the conical bearing point 125 is a 15 thumb screw 127 rotatably mounted in the end of the member 124. This thumb screw has a conical bearing point 128 co-operating with a suitably formed recess in the boss 129. The 20 bosses 128 and 129 are a part of the casing 63 which encloses the driving mechanism for the knife.

The conical points 125 and 128 together form pivots about which the member 124 may be rotated. The deflector 121 is secured to the member 124 by the screws 130 which pass through the deflector and suitably formed bosses 131 (see Fig. 3). If it is desired to entirely remove the deflector, it is only necessary to retract the thumb screw a sufficient amount to withdraw the conical bearing point 128 from its recess and this thereafter causes the deflector to move outwardly away from the knife. Also mounted on the casing 63, is an angular bracket 132, one portion of the angular bracket being held against the casing 63 by means of a screw 133 passing through a slot 134. The other angular portion 135 of the bracket extends outwardly from the casing 63 to form an abutment against which the member 124 is adapted to abut when the 35 same is moved towards the knife, and this portion 135 prevents the deflector from coming too close to the slicing knife 38 and permits one to adjust the deflector as close to the knife as may be desired to prevent scraps from being pushed between the deflector and the knife.

The work clamp shown is of the type described and claimed in my co-pending application, Serial No. 465,597, filed July 3, 1930. As shown, it 50 comprises generally a clamp member 146 carried by the work holder or carriage 23. The clamp member carries suitable substance clamping means thereon, such for example as are shown in the patent to Luschka et al. 1,356,165, dated October 19, 1920, which clamping means are 55 operable to grip or release the substance by means of the handle 153. The clamp 146 is carried by the work holder 23 and hence it is movable therewith as the work holder is moved along the guide rod 8. The clamp, however, is 60 slidably mounted upon the work holder for movement toward and from the gage plate 14 and the cutting plane of the knife. The clamp is movable toward and from the gage plate by means of handle 141 secured to the clamp. It 65 will be seen that the single handle 141 may be utilized both to urge the clamp toward the gage plate and also to reciprocate the work holder 23 along the guide rod 8. Further details of the clamp assembly are not set forth, this assembly 70 being described in detail in said co-pending application, wherein the novel features of the clamp are claimed. For the purpose of the present invention any suitable substance clamp carried by the work holder and movable toward 75 the gage plate and the plane of the cutting

knife could be employed. The clamp could be movable manually or by automatic means.

The operation of the machine as described so far is as follows:

The substance to be sliced is placed on the work holder 23, and the substance is clamped thereon by means of the clamping means. The gage plate 14 is positioned the desired distance away from the cutting plane of the knife by means of the operating knob 94. The operator grasps the handle 141 and exerts a pressure on the work clamp support in a direction longitudinally of the guide 8 and also toward the gage plate. This causes the work holder 23 to move past the cutting edge of the knife and also holds the substance firmly against the gage plate 14.

As the slice is cut from the substance the operator grasps the forward edge of the slice and moves the same in a general direction towards the rear of the machine while the remaining part of the slice is being cut. The clearance space provided for the operator's hand permits him to do this. The substance which remains on the work holder 23 engages the guard plate 101 and is prevented from rubbing against the side of the knife by this guard plate.

After the next succeeding movement of the work holder to the position shown in Fig. 1, the substance is again moved towards the gage plate and the substance is ready to have the next slice cut therefrom.

Ordinarily when a slice is being cut from a substance, the lower edge of the slice which over-hangs the edge of the table is not supported and there is a tendency at least for the lower edge of the slice to be cut ragged. I therefore desire to employ means which supports the lower edge of the slice while it is being severed from the substance. Owing to the sloping surface 35 of the work holder, it is not possible to provide a rigid stationary support since the point of contact between the knife and the lower edge of the substance is always changing and in a vertical direction, in fact the point of contact 40 really moves in an arcuate path which is mostly vertical, due to the arcuate shape of the cutting edge of the knife.

Therefore, in order to properly support the 50 edge of the slice at all times while the slice is being cut, I provide a support for the lower edge of the slice which remains in the same plane as the supporting surface of the work holder at all times during the cutting operation. This means is best illustrated in Figs. 6, 7 and 8 and comprises the arcuate member 173 having the integral slice supporting projection 174 formed at the lower forward edge thereof as best illustrated in Fig. 8. The projection 174 is formed on an outwardly projecting portion 175. The guard 60 55 176 in this instance is mounted rigidly on the member 3 and is secured thereto by means of the screws 177. A long arcuate groove 178 is provided in the guard 176. Rivets 179 pass through the arcuate slot 178 and are secured 65 within the openings 180 of the member 173, thereby holding the member 173 in definite relation to the guard 176, the member 173, however, being permitted to travel longitudinally of the slot 178. Each of the rivets 179 has antifriction rollers 181 mounted thereon for engaging the edges of the slot 178 in order to reduce the amount of effort needed to move the member 173 along the arcuate guard 176.

Since the arcuate guard 176 has its center of 75

substantially the same point as the center of rotation of the knife, it will be seen that the projection 174 will travel along an arcuate path adjacent the cutting edge of the knife as the member 173 moves relatively to the guard 176. In order to maintain the supporting surface of the projection 174 in substantially the same plane as the supporting surface of the table, I provide a cam slot 182 in the edge of the casting 24 which lies adjacent the cutting plane of the knife. I also rigidly mount a pivot pin 183 in the opening 184 of the member 173. On this pivot pin I provide a bearing portion 185 which rotatably supports a roller 186 preferably having the outer peripheral surface thereof substantially arcuate in cross-section as best illustrated in Fig. 7. By this arrangement it will be seen that as the work holder 23 is moved along the guide 8, the roller 186 is caused to travel in the cam slot 182 thereby causing the member 173 to travel upwardly along the guide 176, being guided in this movement by the arcuate slot 178 and the rollers 181. In this manner the supporting surface of the projection 174 always lies in substantially the same plane as the supporting surface of the work holder 23.

In Figs. 9, 10 and 12 I have shown a modification of my invention which embodies a slice receiving platform movable with the work holder. In order to carry out this invention properly I provide the member 3' which corresponds to the member 3 in Fig. 1 with a longitudinal slot 201 in the guard portion 7'. Otherwise the member 3' is the same as the member 3 in Fig. 1.

In the boss 292 on the casting 203 which supports the work holder 204 and which is similar to the casting 14 (Fig. 4), I secure a rod 205 by means of a pin 206, or if desired by means of a set screw. A reinforced skeleton casting 206 has bearings 207 through which the rod 205 extends. Set screws 208 are used to prevent rotational movement of the casting 206 about the rod 205. In order to prevent rotational movement of the casting 206 about the rod 205, I may also employ a square rod extending through correspondingly shaped bearings in the casting or I may use any other desired means for accomplishing this purpose.

On the top of the casting 206, I mount a sheet metal slice receiving plate 209 reinforced by a bead 210, which surrounds the outer periphery thereof. As is best seen in Fig. 9 the clearance space below the knife enables the slice receiver to pass beneath the lower edge of the knife so that the slices will be more effectively deposited on the slice receiving platform. The member 209 is secured to the casting 206 by means of the screws 211, and a handle 212 secured to the casting 206 at 213 provides means whereby the slice receiver may be held when it is desired to remove the same from the rod 205. The handle 212 may also be used to reciprocate the slice receiver and work holder while the operator is holding the substance in the V-shaped work holder 195 and feeding the same towards the cutting plane of the knife. In other words, the operator would grasp the handle 212 with his left hand and hold the substance being sliced with his right hand.

Other modifications of my invention will appear to those skilled in the art to which this invention pertains, and therefore I do not wish to limit myself to the particular features of novelty shown in the accompanying drawings. The scope of my invention is clearly set forth

in the claims which form a part of this application.

Having thus fully described my invention, what I desire to secure by Letters Patent of the United States is:

1. A slicing machine comprising a slicing knife, a work holder, a guide for said work holder, a cover for said guide, and a guard forming an extension of said cover for protecting said guide on the side thereof adjacent said knife, said guard having a longitudinal opening therein, and a slice receiving table having an extension extending through said slot and operatively connected to said work holder, said slice receiving table being adapted to receive the 15 slices as they are cut by said knife.

2. In a slicing machine the combination with a slicing knife, of a work support guided for movement relatively to said slicing knife and being so mounted with respect to said knife 20 that the relative movement between said knife and said work support causes the point of intersection of the cutting edge of said knife with the plane of the supporting surface of said work holder to move along an arcuate path about the 25 center of the knife, a slice support for supporting the lower edge of the slice as it is being cut at all times while the slice is being formed, and means for moving said slice support along an arcuate path parallel to the aforementioned 30 arcuate path in position to engage the said edge of said slice at all times during the formation of said slice.

3. In a slicing machine the combination with a substance support, of a slicing knife movable 35 relatively thereto, the supporting surface of said support being inclined to the path of relative movement of said support and knife and a slice support having means co-operating therewith for causing the same to move so that the 40 operative surface thereof is substantially in the plane of the supporting surface of said substance support at all times during the relative movement of said knife and support, said last mentioned means comprising a guard for the edge 45 of said knife, and co-operating cams on said guard and substance support acting on said slice support to move the same in the aforesaid manner as said knife and support move relatively to each other.

4. In a slicing machine, the combination with a slicing knife, of a work support for supporting the substance while it is being sliced, a gage plate adjustable to various positions in a plane parallel to the cutting plane of said knife, 55 a guard carried by said gage plate for guarding the edge of said knife adjacent thereto, a deflector for deflecting slices as they are formed, a reciprocating work table having a combined substance clamp and feeding means thereon for 60 feeding the substance toward said gage plate so that slices may be cut therefrom, said deflector having a portion thereof extending beneath the edge of said knife to guard the edge of said knife, a rubbing plate adjacent said 65 knife on the same side as said work support for preventing the engagement of the substance with the knife as the substance is moved past said knife by said support, a slice receiver for receiving slices as the same are cut by said 70 knife, said slice receiver being movable with said support and on the side of said knife opposite to said support, a slice support movably mounted adjacent the edge of said first support, and means for moving said slice support during 75

relative movement of said substance support and knife toward each other, in a direction such as to maintain the said slice support always adjacent the edge of said support, and substantially in the plane of the supporting surface thereof, for supporting the slice adjacent the cutting edge of said knife at all times during the formation of the same.

5. In a slicing machine, the combination with a slicing knife, of a work support for moving the work past the knife and for supporting that portion of the substance which is being severed, comprising a table upon which the substance is supported, said table being inclined 10 in the direction of its travel to a plane parallel to its path of travel one edge of said table lying adjacent the cutting plane of the knife, a slice support movably mounted adjacent the forward edge of the knife and having its supporting surface always in substantially the same plane as the supporting surface of said table, and means for moving said slice support so that its supporting surface will always lie substantially in the plane of said table during the reciprocation of said table past said knife.

6. In a slicing machine, the combination with a slicing knife, a substance support movable along a predetermined path, the supporting surface of said table which lies adjacent said knife being inclined in a plane at an angle to the path of travel of said table so that the intersection of a plane through the supporting surface of said table and the cutting edge of said knife changes with respect to a fixed point about 30 the axis of rotation of said knife, a supplemental slice support arranged immediately in front of the knife and guided to travel about the cutting edge of said knife and adjacent thereto at all times during reciprocation of said table, and means for moving said slice support so that said support always is in substantially the same plane as the adjacent supporting surface of said table.

7. In a slicing machine, the combination with a slicing knife, of a trough for supporting the substance to be sliced and movable past the cutting edge of said knife so that substances supported in said trough will have slices cut therefrom by said knife, a slice support arranged adjacent the edge of said trough which lies adjacent the cutting plane of said knife, said slice support having a portion thereof arranged on the opposite side of the cutting plane of said knife from said trough, and means operatively connected to said trough to be actuated thereby and operable when said trough is moved for controlling the movement of said slice support as said trough moves past said knife for retaining said slice support adjacent the cutting edge of said knife and substantially at the same place as that portion of the trough which lies adjacent the cutting edge of said knife, the surface of the trough having portions thereof adjacent the cutting plane inclined at 60 an angle to the path of reciprocating movement thereof.

8. In a slicing machine, the combination with a knife arranged in a substantially vertical plane, a gage plate arranged with the substance 70 engaging surface thereof substantially parallel to the cutting plane of said knife and movable to and from said cutting plane, a substance support having the substance supporting surface thereof extending substantially at right angles to the cutting plane of said knife and recipro-

cable relative to said knife, said gage plate having a plurality of ribs thereon extending substantially parallel to the cutting plane of said knife and to the path of relative reciprocation between said support and knife, and adapted 15 to engage the end of the substance from which the slices are formed as the substance is moved into engagement with said knife to prevent the upward movement of the substance away from said substance support.

9. In a slicing machine, the combination with a slicing knife, of a substance support movable past said knife in a plane substantially parallel to the cutting plane of said knife, a gage plate comprising a substance engaging member arranged substantially parallel with the cutting plane of said knife for limiting the position of the end of the substance adjacent the cutting plane of said knife as the substance is moved along said support toward and against said gage plate, whereby the thickness of the slice to be formed is determined, said member being mounted for pivotal movement in a plane substantially parallel to the cutting plane of said knife from an operative position in which a portion thereof lies closely adjacent the cutting edge of said knife to an inoperative position remote from the cutting edge of said knife, means for normally positively preventing pivotal movement of said member from said operative position to said inoperative position during normal movement thereof to and from said cutting plane, means selectively operable by the operator for permitting said member to be moved to its inoperative position, and means for constraining said gage plate to move in a path wholly to one side of the cutting plane of said knife while being moved to and from said inoperative position, said selectively operable means comprising a releasable adjustable means 35 for permitting extended movement of said member beyond the normal permitted movement thereof in a direction toward and from the cutting plane of said knife, and a guide pin which normally prevents rotative movement of said 40 gage plate during normal movement thereof but which is rendered inoperative when said gage plate is given said extended movement.

10. In a slicing machine, the combination with a slicing knife, of a guard plate positioned adjacent said knife with its substance engaging surface substantially in the cutting plane of said knife, a base for supporting said guard plate, and means for detachably connecting said guard plate on said base comprising downwardly extending pins on said guard plate arranged within openings in said supporting base, the said pins having means thereon for frictionally gripping the walls of said openings, and means for preventing lateral play of said pins within said openings whereby the guard plate is positioned rigidly adjacent the cutting plane of said knife against movement perpendicular to the cutting plane thereof but is readily detachable on movement of said guard plate in a direction parallel to said pins solely by a manual force applied to said guard plate.

11. In a slicing machine, the combination with a slicing knife, of a substance support movable past the cutting edge of said knife to present 70 a substance to be sliced to said knife, a guide rod for guiding said support as said support reciprocates relative to said knife, a cover extending over said guide throughout substantially the entire length thereof and downwardly be- 75

- 5   between said guide and the cutting plane of said knife, said downwardly extending portion having a longitudinal slot therein parallel to said guide rod, a slice receiving table on the same side of said downwardly extending portion of said cover as said knife having an extension extending through said slot and having a portion thereof rigidly secured to said substance support so as to move in unison therewith.
- 10   12. In a slicing machine, the combination with a support, of a slicing knife, a gage plate for gaging the thickness of the slice to be cut, and a mounting for said gage plate comprising a bearing on said support, a shaft extending through said bearing and secured to said gage plate, a pin on said gage plate extending parallel to said shaft and normally arranged within an opening in said support so that upon longitudinal movement of said shaft, said gage plate will move in the direction of the length of the shaft but cannot rotate while said pin is within said opening, and means for moving said shaft longitudinally, said pin being movable out of its bearing on an extended movement of said shaft without releasing said shaft from said bearing, whereby said gage plate can pivot around said shaft to and from an inoperative position.
- 15   13. In a slicing machine, the combination with a support, of a slicing knife, a gage plate for gaging the thickness of the slice to be cut, and a mounting for said gage plate comprising a bearing on said support, a shaft extending through said bearing and secured to said gage plate, a pin on said gage plate extending parallel to said shaft and normally arranged within an opening in said support so that upon longitudinal movement of said shaft, said gage plate will move in the direction of the length of the shaft but cannot rotate while said pin is within said opening, and means for moving said shaft longitudinally, this pin being movable out of its bearing on an extended movement of said shaft without releasing said shaft from said bearing, whereby said gage plate can pivot about said shaft to and from an inoperative position, said pin having friction means associated therewith for frictionally holding said pin firmly within said opening against lateral shifting movement therein.
- 20   14. In a slicing machine, the combination with a support, of a slicing knife, a gage plate for gaging the thickness of the slice to be cut, and a mounting for said gage plate comprising a bearing on said support, a shaft extending through said bearing and secured to said gage plate, a pin on said gage plate extending parallel to said shaft and normally arranged within an opening in said support so that upon longitudinal movement of said shaft, said gage plate will move in the direction of the length of the shaft but cannot rotate while said pin is within said opening, and means for moving said shaft longitudinally, this pin being movable out of its bearing on an extended movement of said shaft without releasing said shaft from said bearing, whereby said gage plate can pivot about said shaft to and from an inoperative position, said pin being split longitudinally and of an outer diameter slightly larger than said opening at the free end of the pin whereby the split portions of said pin are sprung inwardly toward each other when arranged within said opening and prevent any substantial lateral play of said pin within said opening.

15. In a slicing machine, the combination with a support, of a slicing knife, a gage plate for gaging the thickness of the slice to be cut, and a mounting for said gage plate comprising a bearing on said support, a shaft extending through said bearing and secured to said gage plate, a pin on said gage plate extending parallel to said shaft and normally arranged within an opening in said support so that upon longitudinal movement of said shaft, said gage plate will move in the direction of the length of the shaft but cannot rotate while said pin is within said opening, and means for moving said shaft longitudinally, this pin being movable out of its bearing on an extended movement of said shaft without releasing said shaft from said bearing therefor, whereby said gage plate can pivot about said shaft to and from an inoperative position, said means for moving said shaft longitudinally including a spring for moving said shaft in one direction, and a threaded member for moving said shaft against the action of said spring.

16. A device as set forth in claim 12 in which said shaft has a permitted normal longitudinal movement for positioning the gage plate at different distances from the cutting plane of said knife and in which there is a limiting stop for limiting the extent of movement of said gage plate more than a predetermined distance away from the cutting plane of said knife, said shaft having permitted movement beyond the position where it may be arrested by said stop and said stop being releasable to permit said gage plate to have an extended movement beyond said predetermined amount sufficient to remove said pin from said opening and permit rotative movement of said gage plate about the axis of said shaft to a position remote from the cutting edge of said knife.

17. In a slicing machine, the combination with a cutting knife, of a support movable relative thereto, the surface of the substance support adjacent the cutting plane of the knife diverging from the direction of relative reciprocation in a plane parallel to the cutting plane of the knife, whereby the point of intersection of the cutting edge of the knife and the supporting surface extended varies in a direction toward and from a line in the cutting plane of the knife, extending parallel to the path of relative reciprocation, a slice support arranged closely adjacent the cutting edge of the knife having a path of travel substantially parallel thereto, and means for moving said slice support along its path in timed relation to the movement of said support to position the supporting surface of said slice support substantially in the same position relative to the aforesaid point of intersection, substantially at all times during the relative reciprocation of said knife and said support, whereby the slice being formed is supported closely adjacent the cutting edge of the knife at substantially all times during the formation of the slice.

18. A device as set forth in claim 17, in which means is provided for guiding the slice support along its path comprising a member having a slot therein substantially parallel with the cutting edge of said knife, and a pin connected to said slice support, arranged in said slot and guided thereby.

19. A device as set forth in claim 17, in which means is provided for guiding the slice support along its path comprising a member having a

slot therein substantially parallel with the cutting edge of said knife, and a pin, connecting said slice support, arranged in said slot and guided thereby, and in which the means for moving said slice support comprises a guiding means arranged between said slice support and the adjacent edge of said substance support extending parallel to the edge of said substance support, and having means cooperating with means on said slice support.

20. A device as set forth in claim 17, in which means is provided for guiding the slice support along its path comprising a slot substantially concentric with the cutting edge of said knife and a pin connected to said slice support, extending through said slot and guided thereby, and in which the means for moving said slice support comprises an extending portion on said slice support, guided within a slot in the adjacent edge of said substance support extending substantially parallel with the adjacent substance supporting edge thereof, whereby the relative movement of said supporting knife causes the slice support to move arcuately of the cutting edge of said knife while guided by said pin within said arcuate slot, due to the camming action of said extension on said slice support cooperating with the sides of said slot in said substance support.

30. 21. In a slicing machine, the combination with a slicing knife of a substance support guided for reciprocation in a rectilinear path past the cutting edge of said knife, and having the edge of said support adjacent said knife sloping at an angle to the path of reciprocation of said substance support, the said edge having a slot therein, a guard having an arcuate slot therein extending substantially parallel to the cutting edge of said knife and arranged on the side of the cutting plane of said knife opposite to that on which said substance support is arranged, a member guided for movement in said arcuate slot carrying a slice supporting projection,

means connected to said slice supporting projection arranged within a slot in the adjacent edge of said substance support, extending substantially parallel with the supporting surface of said edge of said substance support, whereby the slice supporting projection is caused to move in an arcuate path with the supporting surface thereof always substantially at the point of intersection between the cutting edge of said knife and the supporting surface of said substance support extended.

22. In a slicing machine, the combination with a slicing knife of a substance support movable past the cutting edge of said knife, in a plane substantially parallel to the cutting plane of said knife, a guard plate positioned adjacent the path of movement of said substance support for engaging the end of said substance from which a slice is removed after the substance passes the cutting edge of the knife, said guard plate having the substance engaging the surface thereof formed with a plurality of ribs extending substantially parallel to the path of movement of said substance support to hold the substance firmly on said support as the substance is being sliced, and for preventing the substance from rubbing against the side of said knife, and a gage plate located forwardly of the cutting edge of said knife substantially parallel to said guard plate, for gaging the pick-up of the slice being formed, and for guiding the adjacent end of said substance during the formation of said slice, said gage plate having a plurality of ribs thereon extending substantially parallel to the path of movement of said substance, and to said first mentioned rib, whereby the substance is held down against the substance supporting tresses of said support at all times during the formation of the slice by the ribs on said guard plate and gage plate which lie on opposite sides of the cutting edge of said knife.

JOSEPH FOLK.
